TELEPHONE SYSTEM

Filed April 28, 1928

UNITED STATES PATENT OFFICE

ROMAN TRECHCINSKI, OF WARSAW, POLAND, ASSIGNOR TO TELEFONAKTIEBOLAGET
L. M. ERICSSON, OF STOCKHOLM, SWEDEN, A COMPANY OF SWEDEN

TELEPHONE SYSTEM

Application filed April 28, 1928, Serial No. 273,748, and in Sweden April 30, 1927.

In telephone plants comprising automatic telephone exchanges of different systems the inter-office traffic has hitherto usually been handled by means of operators which receive all incoming traffic from other exchanges and complete the connections either purely manually or in a semi-automatic way using the automatic switches of the exchange. The expression, exchanges of different systems, is here particularly used to denote exchanges having subscribers' lines or junction lines respectively grouped in accordance with different numerical systems, whereas the design of the automatic exchanges as regards constructive features may otherwise be similar or different. The present invention has for its object to provide for a direct automatic inter-office traffic between such exchanges of different systems. Principally, the invention consists therein that the establishment of the telephone connections between exchanges of different systems is effected under the control of a register which is common to all selectors included in the talking connection and which is arranged to control the setting of the selectors during different stages of the switching operation in accordance with different numerical systems corresponding to the systems of the different exchanges included in the talking connection.

The invention will be more closely described with reference to the accompanying drawing, which shows an application of the invention for inter-office working between a telephone exchange having machine-driven selectors adapted to be set by means of retractive or back impulses under the control of registers, on the one hand, and an exchange having electro-magnetically driven selectors adapted to be set by means of forwardly directed impulses, on the other hand. In the drawing only those parts of the talking connection and the appertaining switching apparatus are shown which are required for the explanation of the invention. A calling subscriber's line AL will receive in known manner connection with a first group selector GV₁ through a call finder AS and the appertaining junction line BL. Allotted to a group of such junction lines are a number of registers

consisting of a number of register switches RE₁—RE₅ and a number of control switches RE₆—RE₉. Such a register is automatically connected up to the junction line BL by means of a junction finder RS upon a call occurring. In the example shown it is assumed that the group selector GV₁ can be used both for local connections within the same station and for connections through other stations. The outgoing traffic to telephone exchanges where the selectors are set by means of forward impulses is carried over junction lines CL. Allotted to each of the junction lines last mentioned is an impulse sending device consisting of a number of relays FR, GR, HR, IR, KR and LR, which are automatically brought in operation when the junction line is taken into engagement. Said relays will then send current impulses simultaneously rearwardly to the register and forwardly to the selectors at the other exchange. Said impulse sending device may be arranged at the outgoing or at the incoming end of the junction line. It may, evidently, be replaced by a switch driven electromagnetically or otherwise.

The register switches RE are of the kind which are moved forward for one step when the appertaining operating magnet is energized and for another step when the magnet is de-energized. They are provided with rows of fixed contacts A, B, C etc. so arranged that opposite contacts of each setting position will be electrically connected by the contact arms (not shown) which are arranged to move from the left to the right. By means of a shifting device consisting of a relay UR the contacts of the register switches may be switched over for controlling the setting of the selectors in accordance with different numerical systems. Certain rows of contacts, viz. the rows B, D, G, L, P and R are adapted to come into use only when extending the talking connection to an exchange of another system, whereas the rows of contacts A, C, F, H, I, K, M, O, Q, will come into use only in establishing connections in accordance with the numerical system of the own exchange. The rows of contacts E and N are used in both cases. The

register switch RE_1 comprises the contact row A, the register switch RE_2 the contact rows B and C, the register switch RE_3 the contact rows D, E, F, the register switch RE_4 the contact rows G, H and I, and the register switch RE_5 the contact rows K and L. The contact rows O and P belong to the control switch RE_6 and the contact rows Q and R belong to the control switch RE_7 . The register switches RE_1 to RE_5 have ten positions and are set in accordance with the decimal system. The control switches RE_6 , RE_7 and RE_8 have 25 positions corresponding to the grouping of the lines in 25 groups according to the 25 rows of contacts of the group selectors and the final selector. The control switch RE_9 has twenty positions corresponding to the number of lines in each contact row of the final selector. Instead of providing the different register switches with different series of contacts suited for different numerical systems, it is evidently also possible to use different registers which are brought into operation alternately under the control of the shifting device UR.

In the example shown it may be assumed that the selectors at the first exchange have a capacity of 500 lines, divided into 25 numerical groups of 20 lines in each group, whereas the selectors at the other exchange are assumed to have a capacity of 100 lines divided into 10 numerical groups of 10 lines in each group. At the exchange last mentioned the lines are thus grouped in accordance with the decimal system. It may be assumed that the first station comprises 30,000 subscribers numbered from 10,000 to 39,999 and that the other exchange has 20,000 subscribers numbered from 40,000 to 59,999. In accordance herewith the shifting device UR is operated over contacts K_1 , K_2 in the fourth and fifth positions of the switch RE_1 . The 20 first numerical line groups of the group selector GV_1 are reserved for the traffic to the exchange last mentioned, the different numerical groups corresponding to different thousands of the exchange last mentioned. The junction lines CL extending to this exchange are connected to second group selectors (not shown) adapted for the selecting of the hundreds.

The successive switching in and out of the different register switches is controlled in known manner by means of sequence switches SOR_1 and SOR_2 which are so constructed as to pass to the next contact position only upon the appertaining coupling magnet being de energized. The sequence switch SOR_2 has two contact arms AK and BK .

The operation is as follows. After the calling subscriber has been connected in known manner with a disengaged junction line BL through the call finder AS and to a disengaged register through the junction finder RS , the line circuit 1 is closed through

an impulse relay AR which energizes and closes a circuit 2 for a slow-acting relay BR . The subscriber then operates his impulse sender sending in succession five series of current impulses, by which the register switches RE_1 — RE_5 are successively set in accordance with the number of the subscriber wanted. Said number may in this case be assumed to be 45678. The register switch RE_1 is operated over the circuit 3 which is closed when the impulse relay AR de-energizes a slow-acting relay CR then receiving current over a circuit 4 and closing a circuit 5 for the sequence switch magnet SOR_1 . When after the sending of the first impulse series the impulse relay AR remains de-energized, the relay CR will release its armature causing the magnet SOR_1 to de-energize and to move the sequence switch into the second position in which the register switch RE_2 is connected up for receiving the second impulse series. This switch as well as the remaining register switches will then be set similarly as just described. Immediately after the setting of the second register switch RE_2 the group selector GV_1 was started in a manner which need not be more closely described. During its movement the group selector will send by means of an impulse sender IS current impulses through a circuit 6 including an impulse relay DR which then in turn sends impulses through the control switch RE_6 over the circuit 7. When the switch last mentioned reaches the position which has been marked by the setting of the register switches RE_1 and RE_2 , a circuit 8 is closed through contacts of said switches, the contact arm BK of the sequence switch SOR_2 and a relay ER . The relay last mentioned will then close a circuit 9 over a contact of a sequence switch MRR and through the sequence switch magnet SOR_2 the contact arms AK and BK of the sequence switch being then moved forward for half a step. The circuit 8 is then opened and as a consequence also the circuit 9 is opened the arms AK and BK being then moved forward for another half step to the next position. The group selector GV_1 is now started in known manner to search for a disengaged junction line in the group thus selected. When finding a disengaged junction line the circuit 10 is closed through a sequence switch SOG , the third wire of the junction line CL and a relay FR which now energizes and closes a circuit 11 for the sending of forward impulses to the selectors located at the other exchange. The impulse sending over said circuits is effected by means of a relay IR the circuit 13 of which is closed through a relay KR which now receives current over a circuit 12. The circuit 13, however, contains a slow-acting relay GR in series with the relay IR and as a consequence the relay last mentioned will not be able to attract its armature at once. The relay GR , 130

on the other hand, energizes and closes a circuit 14 for the slow-acting relay HR which in turn short-circuits the relay GR at its contact 15. The relay IR will then receive sufficient current to be able to attract its armature the said impulse circuit 11 being then opened. At the same time a circuit 16 is closed through the impulse relay DR at the register. The slow-acting relay GR will, however, now be de-energized owing to the short-circuiting thereof the relay HR being then de-energized so as to remove said short-circuiting. The current through the impulse relay IR is then again reduced so as to cause the latter to release its armature and to close a line circuit 11 whereas the circuit 16 is opened. The relay IR will thus co-operate with the slow-acting relays HR and GR so as to be alternately energized and de-energized while sending out forward impulses over the circuit 11 and back impulses over the circuit 16. This will cause a simultaneous setting of the group selector connected to the junction line CL, and the control switch RE₇ and this operation will continue till the control switch reaches the position marked by the register switch RE₃, a circuit 18 being then closed through the relay ER. Owing thereto to the sequence switch SOG₂ is now moved forward for another step in the manner above described. The circuit 12 of the relay KR will then be broken for a moment causing the slow-acting relay LR to be operated by a current impulse over the circuit 19. Owing thereto the circuit 13 for the relays GR and IR will be kept open for a period of time which is sufficient to allow the group selector to select a disengaged final selector or connector. When the circuit is then again closed, the relays HR, GR and IR will send out another series of current impulses similarly as just described whereby the connector is set for the selection of the tenth the control switch RE₈ being then stepped forward till it reaches a position marked by the register switch RE₁, in which position a circuit 20 is closed whereby the relay ER is again operated and the sequence switch SOR₂ is again set in the manner above described. By the action of the relays HR and LR the connector will then at the same time be switched over for the selecting of the units. Finally a third series of current impulses will follow whereby the connector is set on to the wanted subscriber's contacts under the control of the control switch RE₉ which is caused to stop in a position marked by the register switch RE₅. In this position a circuit 21 is closed through the relay ER. The talking connection is then completed and the register disengages itself from the junction line BL and is restored to normal position in known manner.

I claim:

1. In a telephone system comprising a plurality of intercommunicating telephone ex-

changes having selector switches of different kinds and lines grouped in accordance with different numeral systems, control mechanisms at one of said exchanges, circuits under the control of said mechanisms for controlling the extension of the talking connection, means for setting said control mechanisms in accordance with the subscriber's number wanted, and means associated with said control mechanisms for varying said circuits, when the connection is extended to another exchange, so as to adapt the control mechanisms for the numerical system of the other exchange. 70

2. In a telephone system comprising a plurality of intercommunicating telephone exchanges having selector switches of different kinds and lines grouped in accordance with different numerical systems, control mechanisms at one of said exchanges, circuits under the control of said mechanisms for controlling the extension of the talking connection, means for setting said control mechanisms in accordance with the subscriber's number wanted, sets of contacts associated with said control mechanisms and adapted to control said circuits for setting the selectors in accordance with different numerical systems, and means under the control of said control mechanisms for switching said sets of contacts alternatively in and out of operation according as the connection is to be extended to a subscriber's line of the same or another exchange. 75

3. In a telephone system comprising a plurality of intercommunicating telephone exchanges having selector switches of different kinds and lines grouped in accordance with different numerical systems, control mechanisms at one of said exchanges, means for setting said control mechanisms in accordance with the subscriber's number wanted, a control impulse circuit for controlling the extension of the talking connection, a stop relay for controlling said impulse circuit, a circuit for said stop relay under the control of said control mechanisms, sets of contacts associated with said control mechanisms and particularly adapted for the different numerical systems of the exchanges, and means under the control of said control mechanisms for shifting the circuit of said stop relay alternatively under the control of the one or the other set of contacts according as the connection is to be extended to a subscriber's line of the same or another exchange. 100

4. In a telephone system comprising a plurality of intercommunicating telephone exchanges having selector switches of different kinds and lines grouped in accordance with different numerical systems, control mechanisms at one of said exchanges each control mechanism comprising a number of register switches to be set in accordance with the subscriber's number wanted, a number of con- 105

trol switches adapted to control the setting of the selectors, sets of contacts on said register and control switches particularly adapted for the different numerical systems of the exchanges, and electrical connections between the contacts of said register and control switches, a control impulse circuit for controlling the extension of the talking connection, a stop relay for controlling said impulse circuit, a circuit for said stop relay under the control of said register and control switches, and means under the control of said register switches for varying the electrical connections between the register and control switches so as to shift the circuit of said stop relay alternatively under the control of one or the other set of contacts according as the connection is to be extended to a subscriber's line of the same or another exchange.

20 In testimony whereof I affix my signature.
